EXHAUST WASHER AND SILENCER

Hiram H. Maxim, George H. Herriott, and Leslie E. Knapp, Hartford, Conn., assignors to The Maxim Silencer Company, Hartford, Conn., a corporation of Connecticut

Application May 13, 1932. Serial No. 611,158

8 Claims. (Cl. 183—21)

This invention relates to devices for silencing the noise incident to the exhaust of internal combustion engines and for removing from the exhaust gas any solid matter carried by it, particularly any such matter as may be in incandescent form.

One object of the present invention is to improve prior devices in which water has been mixed with exhaust gases, particularly in respect to improvements in the manner in which the exhaust gases and the water are carried together through the device so as to secure a maximum silencing as well as cleaning effect of the water. A further object is to eliminate any danger of water being drawn back into the cylinders on stoppage of the motor. A further object is to provide for a complete mixture of the exhaust gases and the water during their passage through the device, and for their complete separation as they pass out of it. Additional objects will appear from the following description and claims.

Referring to the drawing—

Fig. 1 is a central sectional elevation of a device constructed in accordance with the invention;

Fig. 2 is a section on line 2—2 of Fig. 1;

Fig. 3 is a detail on an enlarged scale of parts shown in Fig. 1; and

Fig. 4 is a perspective view, partly broken away, of the complete device.

The silencer is contained within a cylindrical casing 10 having slotted lugs 11 around its lower edge to assist in securing it to any suitable bed. At its bottom the casing is formed with a preferably integral closure 12 having a central aperture 13 surrounded by a boss 14 to which a water outlet pipe may be secured. The top of the casing is closed by a header 15 secured by bolts 16 and a packing 17 to a flange 18 on the casing. At its center this header is formed with a conduit 19 extending into the casing, a boss 20 surrounding the central passage 21 thus formed to permit the attachment of a suitable pipe for conveying the exhaust gases away from the device. The gases are admitted through a port 22 in the upper side wall of the casing, this port being fitted with a boss 23 to which the pipe 24 connecting the silencer to the engine may be attached. Water, conveniently from the engine cooling system, is admitted to the casing through a pipe 25 having a vertically flattened end 26 best seen in Figs. 1 and 4. For cleaning purposes a hand hole, provided with the usual closure 27, is preferably formed in the lower side wall of the casing.

The conduit 19 is provided with an external

flange 30 through which pass a circumferential series of bolts 31. Upon these bolts are strung annular plates 32, 33, and 34, an intermediate annular plate 35 surrounding the series of bolts between plates 32 and 33. Plate 34 is supported by nuts 36 on the bolts 31. Plate 33 is maintained in spaced relation above it by a series of spacing tubes 37, each slipped over one of the bolts, and is formed at its inner circumference with a fillet 38 (Fig. 3) supporting a packing 39 making a water-tight joint against the exterior of the conduit 19. At its outer circumference this plate has a depending flange carrying a plurality of helical vanes 40 which permit the gas and water to pass downward with a whirling motion. The plate 35 is of an external diameter such as to fit snugly within the casing 10 and of an internal diameter large enough to form an annular passage 41 between it and the conduit 19. It is supported upon the plate 33 by a circumferential series of radial lugs or vanes 42 which could be formed on either member but are here shown as carried on plate 35. The topmost plate 32 fits snugly against the conduit 19 but forms an annular passage 43 between it and the inner wall of the casing 10. This plate is supported by a circumferential series of radial vanes 44 carried by it and resting on plate 35. The upper surface of the plate 32 rests against the under side of the flange 30, so that the bolts 31 hold the entire internal assembly in place upon the header 15. By removing this header the parts of the silencer may all be removed at once from the casing for cleaning.

The passage of the exhaust gases and the water through the silencer will now be considered. Coming through the port 22 the exhaust gases from the engine meet the water delivered through pipe 25, the water being forced across the path of the gases in a sort of vertical curtain by the flattened end 26 of the pipe. The gases thus become commingled with the water and fill the upper annular chamber 50 formed by the casing 10, header 15, plate 32, and conduit 19. The only outlet from this chamber is through the relatively constricted annular passage 43 between the plate 32 and the casing. This passage the gases and water traverse together, meeting immediately the upper side of plate 35 which closely abuts the casing, causing an abrupt change in direction with a resulting turbulence and further mixing of the gases and water. The fluids pass between the lugs 44, down the annular passage 41, out between lugs 42, and down between the helical vanes 40.

Emerging from between these helical vanes the now thoroughly commingled fluids enter a lower chamber 51 formed by the casing 10, the closure 12, and the plate 33. Since the gases and water 5 are given a whirling motion by the helical vanes 40 the water and the solid particles are swept down and to the outside of the chamber 51, gradually approaching the outlet 13 as their velocity decreases. The water loses its velocity 10 rather rapidly, owing to the relatively large volume of the lower chamber 51, this action being assisted by vanes 52 hanging down below plate 34 and any large accumulation of water in the chamber thus prevented.

15 Since the gases are whirling within the lower chamber, there might be induced at times a sort of whirlpool or water-spout action which, if not broken up or prevented, might be the cause of water being sucked up the central conduit 19 and so discharged along with the exhaust gases. 20 This would of course be objectionable. In the form of the invention shown this action is effectively broken up by the plate 34 and vanes 52.

The attenuation of the sound waves comprising the exhaust noise is very marked in devices constructed in accordance with the invention. The excellent results attained in practice with this form of apparatus are largely due to the use of relatively large chambers connected by means of passageways of relatively small cross-sectional areas through which the gases and the water pass together in intimate relation. The irregular and inconstant path thus presented to the sound waves offers both high acoustic resistance and high acoustic impedance, causing attenuation both by friction and by change of acoustic impedance along the main acoustic channel.

An important feature of the invention is the protection afforded against the possibility of flooding the engine with water should the drain opening 13 become clogged while the engine is running. Should this happen, and not be detected at once, the water level in the lower compartment would rise until it reached the bottom end of the conduit 19, when it would be blown out through the conduit by the exhaust gases. If the engine is stopped under these conditions, the level of the water within the device is initially considerably below the inlet 22 and no water can flow back into the cylinders until the level has been still further built up. An ample period is thus allowed for the water to be shut off manually before this happens, in case the water supply is not automatically shut off with the engine. In any event the reduced pressure in the exhaust system due to cooling of the engine after it is stopped will not be able (if the water is shut off) to cause the accumulated water to be drawn back through pipe 24, since the level of water will not rise higher than the bottom of conduit 19 during the running of the engine. With the accumulated water at this level the suction resulting from cooling would be satisfied by the drawing of atmospheric air back through the conduit 19.

The device is preferably made of cast-iron, a material well known for its permanence and its ability to resist the corrosive action of hot exhaust gases and water, especially sea water. In cases where extreme light weight is a requirement, as in certain marine installations, the device is readily fabricated from corrosion resisting alloys. The details of the illustrated form of the device have been described fully in the in-

terest of clearness. It will be understood, however, that the invention may be embodied in various specific forms, and that it is not restricted to the details here shown except as specifically pointed out in the following claims.

We claim:—

1. An exhaust silencer and washer comprising a casing divided into an upper compartment and a lower compartment, means in said upper compartment for effecting the entrance of exhaust gas and water, means in said lower compartment for effecting the separate discharge of said exhaust gas and water, said upper compartment communicating with said lower compartment through a series of annular slots. 85

2. An exhaust silencer and washer in accordance with claim 1 in which said annular slots are disposed in vertical space relationship one with the other and are alternately of substantially different mean diameter. 90

3. An exhaust silencer and washer in accordance with claim 1 in which said upper compartment communicates with said lower compartment through a tortuous passageway comprising a series of radially disposed passageways alternating with a series of interposed annular slots of alternately different mean diameter and a plurality of angularly disposed vanes whereby said gases and water are given a whirling motion within said lower compartment. 95

100

4. An exhaust silencer and washer comprising a casing divided into an upper compartment and a lower compartment, means in the upper compartment for effecting the entrance of exhaust gas and water, means in the lower compartment for effecting the separate discharge of said exhaust gas and water, said upper compartment communicating with the lower compartment through a tortuous passageway comprising a series of radially disposed passageways alternating with a series of interposed annular slots of alternately different mean diameter and a plurality of angularly disposed vanes whereby the gases and water are given a whirling motion within the lower compartment, a centrally disposed exhaust conduit positioned within the upper compartment and opening into the lower compartment, and a baffle plate positioned in the lower compartment in line with and below the entrance to the exhaust conduit, said series of passageways and slots being positioned exteriorly of and concentric with the lower end of said upwardly extending exhaust conduit. 105

110

115

120

125

5. An exhaust silencer and washer comprising a cylindrical casing having a removable top header and a bottom header, a centrally disposed exhaust conduit affixed to said upper header, and depending therefrom into the volume of said casing, a series of baffles to form a tortuous passageway affixed to the lower end of and supported by said exhaust conduit, whereby the volume of said casing is divided into an upper compartment of annular shape and a lower compartment of cylindrical shape, openings in said upper compartment for the introduction of exhaust gas and water, an opening in said lower compartment for the discharge of water and means for preventing water spray from entering said exhaust conduit. 130

135

140

6. An exhaust silencer and washer in accordance with claim 5 in which water is introduced into said upper compartment in a spray directed across the stream of incoming exhaust gases. 145

150

7. An exhaust silencer and washer in accordance with claim 5 in which said means for preventing water spray from entering said exhaust

conduit comprises a baffle plate, supported by said exhaust conduit, and positioned within said lower compartment in line with and below the entrance to the conduit, said baffle plate having one or 5 more vertical webs affixed thereto.

8. An exhaust silencer and washer comprising a cylindrical casing having a removable top header and a bottom header, a centrally disposed exhaust conduit affixed to said upper header and 10 depending therefrom into the casing, a series of baffles to form a tortuous pasageway affixed to the lower end of and supported by the exhaust conduit to divide the casing into an upper compartment of annular shape and a lower compartment of cylindrical shape, said baffles including a 15 series of annular slots of alternately different diameter and a series of radially disposed passageways extending between the cylindrical shell of

the casing and the centrally disposed exhaust conduit, the lowest of said slots being provided with a plurality of angularly disposed vanes whereby the commingled exhaust gas and water is given a whirling motion as it enters the lower 80 compartment, openings in the upper compartment for the introduction of exhaust gas and a spray of water, an opening in the lower compartment for the discharge of water, and a baffle plate supported by the exhaust conduit within 85 the lower compartment and in line with and below the entrance to the conduit, said baffle plate having one or more vertical webs affixed thereto.
